COMBINED UMBRELLA AND WRITING IMPLEMENT

Howard A. Fellerman, New York, N. Y.

Application August 16, 1955, Serial No. 37,480

Term of patent 7 years

(Cl. D88—3)

Figure 1 is a front elevational view of a combined umbrella and writing implement, showing my new design in closed position.

The characteristic features of my design reside in the portions shown in full lines in the drawing.

I claim:

The ornamental design for a combined umbrella and writing implement, substantially as shown and described.
